UNITED STATES PATENT OFFICE.

PAUL T. FRANKL, OF NEW YORK, N. Y., ASSIGNOR TO CELLULOID CORPORATION, A CORPORATION OF NEW JERSEY.

DESIGN FOR A PUFF BOX OR SIMILAR ARTICLE.

Application filed December 22, 1928. Serial No. 29,375. Term of patent 3½ years.

To all whom it may concern:

Be it known that I, PAUL T. FRANKL, a citizen of the United States, residing at New York, in the county of New York and State of New York, have invented a new, original, and ornamental Design for a Puff Box or Similar Article, (Case 6), of which the following is a specification, reference being had to the accompanying drawing, forming part thereof.

Figure 1 is a top plan view of a puff box or similar article, showing my new design.

Figure 2 is an end elevation.

I claim:

The ornamental design for a puff box or similar article, as shown.

PAUL T. FRANKL.
